SAFETY MEANS FOR ELEVATORS

Benjamin J. Winner, Chicago, Ill.

Application October 13, 1933, Serial No. 693,449

5 Claims. (Cl. 187—29)

My invention relates to means which may be readily installed intermediate of the power supply and the elevator cab controlling motors and which is adapted to interrupt the power supply 5 to the elevator controlling motor.

The invention has for its object the provision of means operable from the top and the bottom of the cab of the elevator when repairs or adjustments on the elevator are to be made where- 10 by the inadvertent starting or running of the elevator will be impossible.

My invention is particularly adapted for controlling the operation of electrically operated elevators and involves means preferably arranged 15 both on top of the cab and on the bottom to permit the service or repair man to control the circuit while engaged in making repairs either on top or below the cab.

The purpose of my invention is to prevent the 20 accidents that have occurred to men while working on elevators because the elevators were inadvertently started up or down by an uninformed operator or other workman up in the pent house above the elevator-shaft. Many accidents and 25 deaths have resulted in the past because the elevator undergoing inspection or repair may be and often is made to move upwardly or downwardly through manual operation of the magnet control switches situated on the control boards 30 in the pent house or machine room, while the men are working either on top or below the elevator.

With the elevator system equipped with my invention, it will be impossible to move the elevator 35 after my improved means has been actuated by the workman positioned either above or below the elevator-cab, as will more readily appear from a detailed description of the embodiment shown in the accompanying drawing, 40 wherein the figure diagrammatically illustrates an electric circuit and elevator cab provided with my improved means.

While the following is a detailed description of the preferred embodiment of my invention, it is 45 to be understood that I do not intend to limit myself to the specific form disclosed, but intend to cover all modifications and alternative constructions coming within the spirit and scope of the invention as expressed in the appended 50 claims.

As the circuit for operating the elevator is controllable by an operator in the elevator-cab, as well as by a workman in the pent house above the elevator-shaft, my invention contemplates 55 opening the operating circuit by the workman or

repair man through the opening of a small and properly housed switch merely accessible to the workman on top or beneath the elevator-cab.

In the drawing, 10 represents a manually operated switch for controlling the current from the 5 supply lines for operating the elevator; the drawing merely illustrating a single elevator circuit; similar circuit and elements being employed for each elevator-cab. While my improved means has been shown in connection with a widely used 10 two wire direct current system, with slight modifications, the improvement will work equally as well on a three phase, three wire alternating current system.

My improved means involves a pair of suitable 15 and easily operated switches of the type known as three-way switches; one located on top of the elevator-cab 11 as generally indicated at 12, while the other is located on the bottom of the elevator-cab as indicated at 13; both switches 20 being preferably located or enclosed in suitable boxes as shown which are each provided with a small bull's-eye while the switch within the box involves a socket and lamp as at 14 for providing a light signal when the switch has been operated 25 or pulled outwardly from its normal position.

The usual controller mechanism in the elevator-cab 11 is generally indicated at 15; while the key controlled or "baby" switch, controlled by the operator through insertion of his key when 30 assuming control of the elevator, is indicated at 16. This switch 16 is shown open in the drawing and therefore prevents operation of the usual well known elevator motor and motor control switches, which are schematically indicated at 17. The 35 key operated switch 16 controls flow of current to the magnet switch indicated at 18 and which, like switch 16, is also open. If the operator fails to close switch 16, magnet switch 18 will remain open and no current will flow to the motor 40 and motor control switches at 17 and hence operation of the elevator is impossible. As soon as switch 16 is closed, movement by the operator of the controller lever in the cab, permits the elevator-cab to move up or down according to 45 the direction of movement of the control lever. The plunger 19 of magnet switch 18 carries contacts 20, 20 which are adapted to make contact with the contacts 21, 21 and contacts 22, 22, thereby closing the circuit for the motor and 50 control switches generally indicated at 17.

The supply lines 23, 23 instead of leading directly to the contacts 21, 21 of magnet switch 18, as is the case in most circuits as heretofore employed, are connected to contacts 24, 24 because 55

I interpose my safety means operatively between the current supply and the magnet switch 18 which controls current flow to the motors.

- Associated with contacts 24 are contacts 25, 25, 5 and these contacts are adapted to be electrically connected through contacts 26, 26, which are insulatedly mounted on the plunger 27 of the electro-magnet 28. The upper end of the plunger 27 is shown provided with a coil spring 29, which 10 normally maintains the plunger 27 in raised position with contacts 26, 26 in contact with points 24, 24 and 25, 25, thus supplying current by means of wires 30, 30, to contacts 21, 21, of magnet switch 18; and one of the contact points 24 is also connected with a lead line 31 which extends to the operator's key controlled switch 16; while the other contact 24 has lead line 32 which connects with one point or contact in the workman control switches 12 and 13.
- 20 These switches 12 and 13, it will be understood, are of the three-way type so that when these switches, are in normal closed condition, the circuit through wire 33 to magnet 18 is completed. On the other hand, if a workman pulls either 25 safety switch 12 or 13, or both, out of normal main circuit closing position as indicated at 12—(while switch 13 is shown closed)—the current to magnet switch 18 will be disrupted causing the contact carrying plunger 19 to drop to open position 30 indicated and thereby discontinue current flow to the motor.

The plunger 27, below the coil 28, is provided with a pair of contact forming elements 34, 34, insulatedly secured to the plunger and which are 35 adapted to close circuits through the pairs of contacts 35, 36.

The lower end of plunger 27 is shown provided with a small bevelled lip adapted to effect holding relation as indicated at 37, with the bevelled end 40 of the plunger of the latching magnet 38 which is electrically connected with one point of the contacts 36 and with the lead line 39 which leads from the elevator cab switch 16 to the magnet switch 18; the end of the plunger of magnet 38 and the side of the lip on plunger 27 are bevelled 45 to permit the latter to force the former against the action of the spring 38a.

One of the points of contacts 35 is shown connected with lead line 31, while the other point of contacts 35 is shown connected with lead line 33 which has connection with the lamp sockets 14 in the workman or safety switches 12 and 13.

As previously stated, one of the points of contacts 36 is connected with lock-magnet 38, while 55 the other of said points is connected with an intermediate contact point of the three-way switches in both boxes 12 and 13, by means of wire 40.

When switch 10 is moved to circuit closing position current will flow by wires 23, 23 to contacts 60 24, 24, through wire 31, operator's key switch 16, wire 39 to magnet switch 18, wire 41 connected with wire 40 through the normally closed contacts of safety switches 12 and 13, wire 32 back to one 65 of the contacts 24. Current passing through the magnet coil of switch 18 causes the plunger 19 to be drawn upwardly, bringing its contacts 20, 20 into contact with contacts 21, 22 and thereby bringing the motor and motor control switches into the circuit, permitting operation of the elevator.

70 In the event of inspection or repair being necessary, the workman operates or pulls out the switch lever 42 of safety switch assembly or box 12, if the repair is on top or above the elevator; or 75 operates or pulls out switch lever 43 of safety

switch assembly or box 13 if the repair is beneath the elevator. In the drawing, the switch lever 42 of safety switch 12 is shown pulled or opened, thus disrupting the current flow through the coil of magnet switch 18, causing this switch to open as shown and hence breaking the circuit for the motor and motor control switch assembly at 17, preventing operation of the elevator.

When the switch lever 42 is fully pulled out and in contact with the contacts 44, 44, as shown, it 10 closes the circuit of the coil of electro-magnet 28, causing the upper magnetic portion of plunger 27 to be drawn down against the action of spring 29, and inducing the lower end to pass the end of the spring controlled locking plunger of magnet 15 38, thereby locking plunger 27 in the lowered position shown in the drawing. When the plunger 27 is in this lowered position, the contacts 34, 34 carried by the lower end of the plunger will be in contact with contacts 35, 36, thereby providing 20 current for the lamp 14 of safety switch assembly 12; the lighted bulb indicating to the workman on top of the elevator-cab 11 that the safety device in the machine room has locked itself open and cut off all power feed going to the control board of 25 the elevator.

At the same time the plunger 27 at its upper end will make contact at 45, 45, which will light up the bulb in the "Danger" sign shown at 46 which is located in the machine room and which will indicate to others in the room that a workman is working on that elevator.

When the workman has completed the repairs and after leaving the elevator, he pushes lever 42 of safety switch 12 completely inward, thereby 35 opening the circuit of coil magnet 28 and subjecting the plunger 27 to the upward force of spring 29. In view of the latching relation between plunger 27 and the plunger of magnet 38, plunger 27 cannot move upwardly. When safety switch 12 is pushed in completely, it partially closes the circuit of coil 18; the circuit of this coil not being completely closed until the safety switch 13 also is pushed in to reset or normal position and the operator's key switch 16 (which the operator is 40 also supposed to have opened) is also closed.

Even though the workman or safety switches 12 and 13 are closed, the elevator cannot be moved by manual operation of any switch in the machine room until the operator in the elevator has closed 50 the switch 16. Closing this switch then causes current to pass through the coil of magnet switch 18, inducing plunger 19 to rise and close contacts 21 and 22 through contacts 20, 20, and also allows current to pass through the coil of latching mag- 55 net coil 38 through the contact 34, 36, causing the plunger of latch coil 38 to retract from locking relation with plunger 27, which permits spring 29 to force plunger 27 into position to again close contacts 24—25—26.

60 This upward movement of plunger 27 causes it to break contacts 45, 45; 34—35 and 34—36. Breaking contact at 45, 45 cuts the current for the "danger" bulb at 46, located in the machine room; while at 34—35 it shuts off current to the 65 lamps 14 of the safety switch boxes 12 and 13; and at 34—36 it breaks the circuit of the latching magnet coil 38, leaving the circuits in the original, normal working condition.

In the exemplification, I show protecting fuses 70 at 47, 47 and 48, 48; fuses 47, 47, being employed by me to protect my safety mechanism in the event of an "overload" or "short"; these fuses 47, 47 being preferably employed in addition to the 75

fuses 48, 49, which are generally employed in the circuit.

As is apparent from the foregoing description, when the workman pulls out either switch 12 or 13, two operations are performed; first, it breaks or opens the circuit of the usual magnet switch 18 generally located on the control board in the machine room, thus making it impossible for an operator in the elevator to operate the latter; and, secondly, the circuit, through the coil 28 of my improved safety means, is closed, energizing this coil and causing the contact carrying plunger 27 to be moved from normal position to a point where it will be engaged by the locking means. It will be understood, of course, that my improved safety means is properly mounted in an enclosure or metallic box located in the machine room and normally not accessible.

My improved means or safety device is comparatively simple in installation and operation, being illustrated in conjunction with a two wire direct current system more or less universally used, wherein the power lines or leads 23 are generally lead to the contacts 21 of the magnet switch 18, whereas with my safety device interposed the power or current supply lines 23 are shown leading to the contacts points 24, 24 of my safety means.

With my improved safety means accidental or unauthorized operation of the elevator through manual operation of the usual magnet control switches at 18-19, (which are usually situated on control boards in the pent house or machine room) will be impossible. With the mechanisms and switches generally employed in the elevator circuits, the safety of a repair man depends entirely upon no one tampering with the magnet control switches referred to, even though the operator's switch 18, is open. Many accidents and deaths have occurred in the manner mentioned. With my device, however, the operation of the elevator is entirely in the control of the repair man through his operation of either switch 12 or 13, whereby the usual magnet control switch at 18-19 is not only opened but the circuit of this switch is disrupted by the operation of plunger 27, which is automatically locked in this position, thus making accidental or unauthorized operation of the usual magnet control switch 18-19 impossible.

What I claim is:

1. Safety means for elevators comprising, in combination with the electric current supply lines, the elevator motor, the motor control switch, circuit closing switch in the elevator cab and the magnet switch interposed between said circuit closing switch and the elevator motor; means whereby current flow to the motor and motor control switch may be discontinued, said means being electrically interposed between the supply lines and the magnet switch and comprising an electro-magnet, a contact carrying plunger adapted to be moved into two positions, one of said positions normally closes the main circuit magnet switch, while the other position of said plunger is assumed when the electro-magnet is energized and the circuit of said first mentioned magnet switch thereby opened, and manually operated auxiliary switches carried by the elevator-cab whereby current to said second mentioned electro-magnet is supplied and said plunger moved into main circuit breaking position.

2. Safety means of the character described adapted to be electrically disposed intermediate of the current supply lines and the elevator motor switch and controls, comprising a magnet coil in

a normally open circuit; a plunger controlled by the coil and normally adapted to close the main circuit of the elevator motor switch and controls when in one position and also adapted to move to a second position when said coil is energized and thereby open the motor switch circuit and close a secondary signal circuit and manually operated switches arranged intermediate of said main circuit and the normally open circuit of said magnet coil whereby the normally open circuit is closed, the magnet coil energized and the plunger moved from its first mentioned normal position and the main circuit thereby opened.

3. Safety means of the character described adapted to be electrically interposed between the current supply and the main magnet coil switch in the elevator motor circuit and comprising a spring controlled contact carrying plunger for normally maintaining the circuit of the magnet coil switch when in one position and to close a secondary signal circuit and partially establish a locking means releasing circuit when moved from normal position into a second position; an electro-magnet coil associated with the plunger; automatic means whereby the plunger is locked in its secondary circuit closing position; and manually operated switches mounted on the elevator and independent of the usual elevator operating controls whereby the second mentioned electro-magnet coil is energized when said switches are closed, said plunger moved to its second position where the elevator operating current supply is disrupted and the plunger moved into engagement with said automatic locking means.

4. Safety means for elevators of the character described, adapted to be disposed intermediate of the current supply and the elevator motor switch and controls and comprising a manually operated auxiliary switch carried on the elevator and interposed between the current supply lines and the elevator motor switch, a contact carrying element normally adapted when in one position to close the main circuit of said motor switch and when in a second position to establish a signal circuit and to prepare a locking means circuit; an electro-magnet coil interposed between the main circuit and said auxiliary switch and adapted to move said element from its normal position into the second or signal circuit making position; and locking means electrically disposed between the motor switch and a contact point of the second position of said contact carrying element.

5. Safety means of the character described adapted to be electrically interposed in the main operating circuit intermediate of the current supply and the elevator motor switch and controls and comprising the combination of a spring controlled contact carrying plunger adapted to close the circuit of the motor switch when in one position and to open said motor switch circuit and to close a secondary signal providing circuit and partially completing a plunger locking means circuit when moved against the action of the spring into a second position; an electro-magnet coil interposed in the main circuit in advance of the motor switch and adapted when energized to move said plunger against the action of its spring and thereby open the main elevator motor switch operating circuit; a locking member adapted to automatically lock said plunger in its main circuit opening or second position; an electro-magnet coil arranged in said locking means circuit and adapted when energized to move said locking member out of plunger locking position; and a manually operated auxiliary switch ar- 75

ranged on the elevator beyond the control of the operator cab electrically intermediate of the main circuit and said first mentioned coil whereby current to said first mentioned coil is provided when the switch is moved out of its first or normal position, said plunger thereby moved against the action of its spring and the elevator motor switch

circuit disrupted, the signal providing circuit closed and said plunger locking means circuit partially completed and said second coil of said locking means circuit being energized when said auxiliary switch is moved back to its first or normal position. 5

BENJAMIN J. WINNER.
